(57) **CLAIM**

The ornamental design for a head for shaver, as shown and described.

DESCRIPTION

FIG. 1 is a perspective view of a first embodiment showing a head for shaver according to our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of a second embodiment showing a head for shaver according to our design;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a perspective view of a third embodiment showing a head for shaver according to our design;

FIG. 16 is a front elevational view thereof;

FIG. 17 is a rear elevational view thereof;

FIG. 18 is a right side elevational view thereof;

FIG. 19 is a left side elevational view thereof;

FIG. 20 is a top plan view thereof;

FIG. 21 is a bottom plan view thereof;

FIG. 22 is a perspective view of a fourth embodiment showing a head for shaver according to our design;

FIG. 23 is a front elevational view thereof;

FIG. 24 is a rear elevational view thereof;

FIG. 25 is a right side elevational view thereof;

FIG. 26 is a left side elevational view thereof;

FIG. 27 is a top plan view thereof;

FIG. 28 is a bottom plan view thereof;

FIG. 29 is a perspective view of a fifth embodiment showing a head for shaver according to our design;

FIG. 30 is a front elevational view thereof;

FIG. 31 is a rear elevational view thereof;

FIG. 32 is a right side elevational view thereof;

FIG. 33 is a left side elevational view thereof;

FIG. 34 is a top plan view thereof;

FIG. 35 is a perspective view of a sixth embodiment showing a head for shaver according to our design;

FIG. 36 is a front elevational view thereof;

FIG. 37 is a rear elevational view thereof;

FIG. 38 is a right side elevational view thereof;

FIG. 39 is a left side elevational view thereof; and,

FIG. 40 is a top plan view thereof.

(Continued)

The portions of the head for shaver shown in broken lines are included for the purpose of illustrating unclaimed portions of the head for shaver and form no part of the claimed design.
